United States Patent Office.

JOHN C. CLIME, OF PHILADELPHIA, PENNSYLVANIA.

Letters Patent No. 96,396, dated November 2, 1869.

IMPROVED CHILD'S CARRIAGE AND VELOCIPED COMBINED.

The Schedule referred to in these Letters Patent and making part of the same.

To all whom it may concern:

Be it known that I, JOHN C. CLIME, of Philadelphia, Pennsylvania, have invented a new and useful Combined Carriage and Velocipede; and I do hereby declare that the following is a full and exact description of the construction and operation of the same, reference being had to the annexed drawings, forming part hereof.

The vehicle herein described is designed for children's use, its principal features being its capacity of change from the appearance and condition of a carriage, to the appearance and condition of a velocipede, and *vice versa*, at will; second, its adaptability, when used as a velocipede, to children of different lengths of legs.

In the drawings—

Figure 1 is a longitudinal vertical section, taken on a middle line of the vehicle, when arranged as a velocipede, the carriage-body and the carriage-handle being removed.

Figure 2 is a perspective view of the carriage-body detached.

Figure 3 is a diametrical section of the front wheel, and a longitudinal section of the crank, employed to turn the front wheel.

Figure 4 is a perspective view of the carriage-handle detached.

Figure 5 is a perspective view of the vehicle, arranged as a carriage, the cranks being removed.

Referring to the drawings—

a, figs. 1 and 5, is a recessed piece of wood or metal, forming the front supporting-part of the running gear.

b is a forked brace, by which the hind axle is attached to the piece *a*.

The brace *b* is provided with several holes *c*.

d and *e* are two spring-braces, to which is secured the seat *f*, which also is provided with holes *s*, corresponding with holes *c* in the brace.

g, figs. 4 and 5, is the carriage-handle, which is detachable, it being fastened to the hind axle, and also to the seat *f*, by thumb-screws, as shown.

h, fig. 1, is a bolt, which passes through seat *f* and front supporting-piece *a*, and also through one of the holes *c* in brace *b*.

A nut and thumb-nut are applied to the lower projecting end of bolt *h*, which, in connection with brace *b*, form a swivel or hinge-joint. This joint, being a little loosened when the vehicle is arranged as a velocipede, allows the front running gear to be guided at the will of the rider.

The hub *i* of the front wheel is tubular, and being extended through a socket formed for it in the piece *a*, it constitutes the journals of the front wheel.

k k, figs. 1 and 3, are the two cranks by which the front wheel is turned.

The crank *k* is made fast to the axle *m*, which passes through the tubular hub *i*, and its projecting end is provided with a right-hand screw-thread, as shown. The eye of the crank *k* is also provided with a similar screw-thread, and is screwed on to the projecting end of the axle *m*; or if the crank *k* be passed through the hub, in the direction contrary to that shown, the projecting end of the axle should be provided with a left-hand screw-thread, so that in either case, the action of the feet on the cranks, in forcing the velocipede forward, tends to tighten the loose crank against the end of the journal.

n, figs. 2 and 5, is the carriage-body, which is made to conform to the shape of the seat *f*, and being placed on seat *f*, is secured in position by means of a thumb-screw, *p*, which passes through an eye in one prong of the handle *g* into the seat *f*.

When the vehicle is to be used as a carriage, the cranks *k k* may or may not be removed, as desired; and when it is to be used as a velocipede, the carriage-body is removed, and the carriage-handle is either removed or allowed to remain in place, as desired.

Having thus described my invention,

I claim, and desire to secure by Letters Patent—

1. Combining, with a velocipede, a detachable carriage-body, and thus forming a vehicle, capable of being arranged either as a carriage or velocipede for children, substantially as set forth.

2. Making said vehicle, when used as a velocipede, adaptable to children, having different lengths of legs, by shortening or lengthening the brace *b*, substantially as described.

3. The combination of the removable handle *g* with the seat *f*, carriage-body *n*, and running gear, all substantially as described and shown, for the purposes specified.

JOHN C. CLIME.
